Primary Examiner — Marcus A Jackson(74) *Attorney, Agent, or Firm* — The Dobrusin Law Firm, P.C.; Bryan S. Lemanski(57) **CLAIM**

The ornamental design for a headlight guard, as shown and described.

DESCRIPTION

FIG. 1 is a perspective view of the present design.

FIG. 2 is a front elevational view of FIG. 1.

FIG. 3 is a back elevational view of FIG. 1.

FIG. 4 is a top elevational view of FIG. 1.

FIG. 5 is a bottom elevational view of FIG. 1.

FIG. 6 is a first side elevational view of FIG. 1; and, FIG. 7 is a second side elevational view of FIG. 1.

The broken lines which define the bounds of the claimed design form no part thereof and are used to show environmental structure.

1 Claim, 6 Drawing Sheets(56)
